UNITED STATES PATENT OFFICE.

MARCELLUS S. FIELD, OF BOSTON, MASSACHUSETTS, ASSIGNOR OF TWO-THIRDS TO JAMES T. A. LEWIS AND JOHN THOMAS WARD, OF SAME PLACE.

DESIGN FOR A RIM FOR MAIL OR PACKAGE BAGS.

SPECIFICATION forming part of Design No. 32,790, dated June 5, 1900.

Application filed May 3, 1900. Serial No. 15,420. Term of patent 14 years.

To all whom it may concern:

Be it known that I, MARCELLUS S. FIELD, a citizen of the United States, residing in Boston, in the county of Suffolk and State of Massachusetts, have invented and produced a new and original Design for Rims for Mail or Package Bags, of which the following is a specification, reference being had to the accompanying drawings, forming part thereof.

10 Figure 1 is a perspective view of a rim for mail and package bags, showing my new design. Fig. 2 is an edge elevation of the same.

As shown in the drawings, the leading or material feature of my design consists of a 15 rod round in cross-section, bent into a general rectangular shape—that is to say, one which has straight outside sides and rectangular outside corners—and with corner-pieces arranged as below described. The ends of 20 this rod are connected by a tube or ferrule *a*, and thence the portion *A* extends at a slightly-upward angle or incline to the first corner, where it bends at *A'* at a right angle, at *A''* at an angle of about forty-five degrees 25 toward the portion *A* and at a sufficiently-downward incline to underlap said portion *A*, and at *A'''* at an angle of forty-five degrees along and under the portion *A* to the corner *A'''*. Thence the rod bends at an 30 angle of ninety degrees, and the portion *B*

extends at a slightly-upward incline to the corner *B'*, at which it describes, at *B'', B'''*, and *B''''*, bends which are exactly similar to the bends *A' A'' A''' A''''*. The third side of the rod *C* is exactly the same as *B* and is at 35 its end formed with the bends *C' C'' C''' C''''*, and the side *D* is similar to the sides *B* and *C* and is provided at its end with the bends *D' D'' D''' D''''*, and the portion *E* of the rod joins and is in line with the portion *A*, said 40 portions *E* and *A*, with their connection *a*, constituting one of the four sides. It will be seen that the sides and the corner-pieces are all the same, each side *E*, *A*, *B*, *C*, and *D* inclining upward toward its left-hand corner, 45 each diagonal portion—that is, between *A''* and *A'''*, *B''* and *B'''*, *C''* and *C'''*, and *D''* and *D'''*—inclining downward toward the right and the other portions being parallel with the main portions *E*, *A*, *B*, *C*, and *D*. 50

Having described my invention, what I claim as new, and desire to secure by Letters Patent, is—

The design for a rim for a mail and package bag, as herein shown and described.

MARCELLUS S. FIELD.
